JOHN CUMMINGHAM, ONE-EIGHTH TO PETER P. CONWAY, AND ONE-EIGHTH TO
PATRICK P. CONWAY, ALL OF PHILADELPHIA, PENNSYLVANIA.

MACHINE FOR SEPARATING ORES.

1,236,133.

Specification of Letters Patent. Patented Nov. 26, 1912.
Application filed June 16, 1910. Serial No. 240,132.

To all whom it may concern:

Be it known that I, JOHN M. SHADEL, a citizen of the United States, residing in Philadelphia, Pennsylvania, have invented Machines for Separating Ores, of which the following is a specification:

One object of my invention is to provide a novel apparatus for separating valuable ore or metal from gangue, which shall utilize the property of a film or layer of oil of preventing the passage through it of such valuable material when this is in finely divided condition.

It is further desired to provide a relatively simple, substantial and easily operated machine for carrying out the above method;—the invention particularly contemplated novel means for insuring the uniform delivery of the pulverized ore, etc., to a body of oil and water and thereafter insuring the separation of the oil with the material which it carries, from the water and less valuable material therein.

Another object of the invention is to provide a novel form of ore treating machine which shall include a simple and efficient device for mixing the oil and water preparatory to their delivery to the ore receiving table, together with a simple and effective device for distributing the pulverized ore over the body of liquid on said table with a view to insuring its thorough treatment and the recovery of its valuable constituents.

I also desire to provide a machine having the above characteristics, with means for preventing clogging of the ore hopper with damp or wet materials;—which means shall also insure the even feed of the ore to the member whereby it is delivered to the liquid.

These objects and other advantageous ends I set forth hereinafter set forth, reference being had to the accompanying drawings, in which,

Figure 1 is a longitudinal vertical section of a separating machine constructed according to my invention; and

Fig. 2 is a plan of the machine shown in Fig. 1.

In the said drawings, 1 represents a supporting frame on which is mounted a flat table 2 inclined at an angle preferably of from 10° to 15° to the horizontal. This is provided with sides 3 and has its upper edge connected to the longitudinal edge of a trans-

versely extending semi-cylindrical container 4 whose second longitudinal edge is extended upwardly to form a back 21. Rotatably mounted within the mixing-chamber provided by said container is a shaft 22 having a series of arms or paddles 23 for agitating and assisting in the delivery of liquid from said chamber to the top of the table 2.

Within the space defined by the sides 3 and back 21 are two transverse walls 25 and 26 co-operating with said members to 25 form a hopper having a narrow, transversely extending delivery opening. The back 26 of this hopper projects below the front wall 25 thereof and terminates in a flat delivery plate 12, spaced above and extending parallel with the table 2 for a short distance adjacent its top end. A second horizontal shaft 8 is mounted in suitable bearings in the sides 3 above the delivery plate, and has on it a cylindrical brush 11 whose bristles 75 or other elements are of such a length as to extend into contact with or immediately adjacent said plate so as to receive material from the delivery opening of the hopper, and under operating conditions, spray it outwardly in a shower so that it falls and is distributed with substantial uniformity over the surface of the main part of the table 2.

Extending transversely within the hopper is a longitudinally reciprocable rod 28 having mounted on it a sleeve 4 from which a series of teeth 5 project downwardly adjacent the back wall 26 and through the elongated delivery opening. Said rod 28 is extended beyond one side 3 of the separator 26 where it is periodically engaged by a cam 6 actuated through a link 27 from a crank 7 mounted on the shaft 8 and the arrangement is such that as this shaft is turned from a suitable source of power through a pulley 9, the crank 7 so actuates the cam 6 as to move the rod 28 and with it the fingers 5, in one direction in the lower part of the hopper. A spring 29 confined between one end of the sleeve 4 and the adjacent side 3 100 of the separator, is compressed by such movement of the rod and when this ceases, acts to return the parts to their original positions.

Supported a short distance above the lower end of the table 2 is a skimmer plate 17 having its horizontally extended upper edge made relatively sharp for about the

length of the middle third of the width of the table. Wing walls 30 lead from the sides 3 to the ends of this sharp edge which has end and side walls 31, 32 and 33, as well as a laterally extended portion whereby material collected from the table is delivered into a trough-like structure 34 leading to any desired receptacle (not shown) at one side of the separator. The wing walls 30 are continued under the skimmer plate 17, below which the table terminates in an apron 18, delivering into a concentrator trough 19 inclined at an angle of about 30° to the horizontal so as to receive water and solid material carried thereby from the table 2. This trough has a series of transverse riffles 20 arranged in the customary manner for catching and retaining relatively heavy and usually valuable nuggets, or particles while permitting the gangue, etc., to pass off.

In any suitable position such as upon the back structure 21, I mount a tank 35 for the reception of oil to be delivered to the machine. This tank is connected through a valved conduit 36 with the container 13 which is also supplied with water through an inlet pipe 37.

Under conditions of operation, oil or other equivalent liquid is delivered at a slow rate from the tank 35 through the pipe 36 to the mixing container 13 which is supplied with water through the pipe 37. The brush-carrying shaft 8 is turned by power applied to the pulley 9 and through a second pulley 38 power is transmitted through a belt 39 to a pulley 40 on the shaft 22, so that the paddles carried by the latter operate to thoroughly mix the oil and water in the container 13. The flow of water and the action of these paddles is such that the mixture of oil and water is constantly delivered to the top of the table 2 over which it flows in a continuous sheet consisting of a layer of water completely covered by a film or layer of oil. The brush 11 is turned by the mechanism above described, in the direction indicated by the arrow, Fig. 1, and pulverized ore from the hopper 10, passes through the delivery opening thereof onto the plate 12 and under the brush 11, which sprays it outwardly so that it falls with substantial uniformity over the sheet of liquid flowing downwardly over the table 2. Any clogging of the delivery opening of the hopper is effectually prevented by the continued reciprocation of the fingers 5 therein which also act to cause the finely divided material to be evenly delivered to the full length of the plate 12.

I have discovered that under the conditions above noted, the layer of oil on the sheet of water flowing downwardly over the table 2 will retain the finely divided metals and more particularly the finely divided

gold which it has been extremely difficult in the past to recover, whereas the sand and other relatively worthless material pass through the oil film into and through the body of water.

The height of the sharp edge 17 of the skimmer above the top surface of the table 2 and the rate of flow of liquid over the latter are such that said edge skims or separates the oil with the solid material which it carries from the top surface of the deepened body of material directed toward it by the converging side walls, delivering it to the trough 21 and thence to any desired receptacle. The water with the sand, etc., passes under the skimmer and is delivered over the apron 18 to the top of the concentrating trough 19, where any small nuggets or bodies of precious metal too heavy to be retained by the oil film, are caught and retained by the riffles 20, while the water and gangue pass out of the lower end. The oil is separated from the solid material carried thereby in any desired manner known to the art as by centrifuging, and from time to time the valuable material gathering above the riffles is collected.

It is to be particularly noted that because of the thorough mixture of the oil and water and of the manner of its delivery from the container 13, the liquid sheet flowing down over the top of the table at all times consists of a layer of water with a complete cover of oil over the same, while by reason of the ore delivery mechanism employed, the pulverized ore under treatment falls upon such liquid sheet in a uniform spray so that the possibility of its entering the latter in large or compact masses which would obviously not be acted on in accordance with my invention, is effectually prevented.

By the use of the skimmer illustrated, the oil with the valuable material carried thereby is completely separated from the water and the relatively valueless solid substances therein:—it being noted that while the body of the table receiving the pulverized ore from the brush is relatively wide to assure of the certain contact of all of the ore particles with the oil, the narrowing of the liquid body at the lower end of the table gives it depth which permits of the effectual separation of oil with its contents from the water and gangue.

I claim:

1. The combination in an ore separator of an inclined table; means for delivering to the upper part thereof liquids of different specific gravities; an ore hopper; a rotary brush mounted to receive pulverized ore from the hopper and deliver it in the form of a spray of solid particles to the liquids on the table; a skimming device mounted at the lower end of the table in position to separate the upper layer of liquid with its con-

tained solid material from the balance of the liquid; and a conduit for the reception of the liquid collected by the skimmer.

2. The combination of a container having

5 an inclined bed; a device for mixing liquids of different specific gravities positioned to discharge the mixed liquids in a sheet over said bed; a device for spraying pulverized ore on the bed; and a conduit having an 10 inlet provided with a relatively sharp edge extending transversely of the bed at the lower portion thereof in position to receive and separate the upper layer of liquid flowing on the bed from the balance thereof.

15 3. The combination of a container having an inclined bed; means for delivering oil and water to the upper portion of said bed; a hopper for pulverized ore; a rotary brush adjacent the upper end of the bed in position 20 to receive ore from the hopper and deliver it in a spray to the liquid on the bed; a skimming device mounted at the lower end of the bed; and a conduit for receiving liquid collected by the skimming device.

25 4. The combination of a container having an inclined bed; a mixing chamber mounted at the upper end of said container in position to deliver liquid thereto in the form of a sheet; means for delivering oil and water 30 to said mixing chamber; an agitating device in the mixing chamber; means for delivering a spray of finely divided ore to the flowing liquid on the bed of the container; and a skimming device at the lower end of the 35 container.

5. The combination of a container having an inclined bed; a device for delivering oil

and water to the upper part of said container; a hopper mounted over the container; a delivery plate in position to receive pulverized ore from the hopper; a 40 rotary brush receiving material from said plate and positioned to deliver the same in the form of a spray to the bed of the container; with a skimming device at the lower 45 end of the container.

6. The combination of a container having an inclined bed; means for delivering oil and water to the upper portion of said bed; a hopper having a narrow outlet elongated 50 transversely of the container; a delivery plate under said outlet; an ore agitating device operative adjacent the outlet of the hopper to distribute the material therefrom upon the plate; a rotary brush operative on 55 the plate and positioned to spray material therefrom over the bed of the container; and a device at the lower part of the container for separating the oil with its contained solid material from the water.

7. The combination of a container having an inclined bed; means for delivering a sheet of superposed oil and water in the upper part of the container; means for spraying pulverized ore upon the sheet of flowing 65 liquid; a delivery trough having an inlet provided with a relatively sharp edge extending transversely of the lower portion of the bed of the container and of a length less than the width of the bed; with wing walls 70 leading from the ends of said sharp edge to the side walls of the container.

In witness whereof I affix my signature.
JOHN M. STADEL.
